UNITED STATES PATENT OFFICE

147,590

DESIGN FOR A LAMP

Arthur Frank Klingberg, Chicago, Ill., assignor to Ray A. Schober, Chicago, Ill.

Application December 5, 1945, Serial No. 124,373

Term of patent 7 years

(Cl. D48—20)

To all whom it may concern:

Be it known that I, Arthur Frank Klingberg, a citizen of the United States, residing at Chicago, in the county of Cook and State of Illinois, have invented a new, original, and ornamental Design for Lamps, of which the following is a specification, reference being had to the accompanying drawing, forming a part thereof.

Fig. 1 is a perspective view of a lamp, showing my new design;

Fig. 2 is a front view of the globe portion on a somewhat enlarged scale; and

Fig. 3 is a top plan view of the globe portion on the same scale as Fig. 2.

I claim:

The ornamental design for a lamp, substantially as shown.

ARTHUR FRANK KLINGBERG.
